POURING SPOUT FOR A BOTTLE OR THE LIKE

Dale R. Khoury, 312 Cogswell Drive, Silver Lake, Wis.
53170, and John J. La Violette, Box 51, Camp Lake,
Wis. 53109

Filed July 29, 1971, Ser. No. 167,562

Term of patent 14 years

Int. Cl. D9—07
U.S. Cl. D9—277

FIG. 1 is a side elevational view of a pouring spout for a bottle or the like embodying our new design, the opposite side being substantially a mirror image of the side shown;

FIG. 2 is a front elevational view;

FIG. 3 is a rear elevational view;

FIG. 4 is a top plan view;

FIG. 5 is a bottom plan view; and

FIG. 6 is a perspective view showing another embodiment of our new design.

We claim:

The ornamental design for a pouring spout for a bottle or the like, as shown and described.
